UNITED STATES PATENT OFFICE.

CHARLES E. BROWN, OF LAWTON, OKLAHOMA.

SLUICE.

1,260,749.

Specification of Letters Patent. Patented Mar. 26, 1918.

Application filed March 26, 1917. Serial No. 157,520.

To all whom it may concern:

Be it known that I, CHARLES E. BROWN, a citizen of the United States, residing at Lawton, in the county of Comanche and State of Oklahoma, have invented certain new and useful Improvements in Sluices, of which the following is a specification, reference being had to the accompanying drawings.

10 This invention relates to certain improvements in sluices and it is an object of the invention to provide a device of this general character having novel and improved means whereby effective agitation may be imposed upon the value bearing material and whereby a materially large tonnage is afforded.

It is also an object of the invention to provide a novel and improved device of this general character comprising a box mounted 20 for vibratory movement together with an agitating member positioned within the box and also mounted for vibratory movement, and wherein said box and agitating member are operated in unison but in reverse directions.

A still further object of the invention is to provide a device of this general character including a box mounted for vibratory movement and wherein said box is provided with 30 novel and improved means for collecting the heavy material or concentrates.

Furthermore it is an object of the invention to provide a novel and improved device of this general character including a box 35 mounted for vibratory movement and wherein the discharging end portion of the box is provided with a well adapted to collect the heavy material or concentrates and wherein said well is provided with a valve-controlled discharge opening for emptying the well of the matter collected therein.

The invention also has for an object to provide a novel and improved device of this general character including a box mounted 45 for vibratory movement and provided at its discharging end portion with a collecting well, together with an agitating member co-acting with the box and with the well.

Also an object of the invention is to provide a novel and improved device of this

general character including a vibratory box together with a conveyer coacting with the discharge end of the box, and wherein said conveyer coacts with the upper portion of the box to collect the by-products or waste 55 material.

The invention consists in the details of construction and in the combination and arrangement of the several parts of my improved sluice whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be the better understood, I will now proceed to describe the same with reference to the accompanying drawings, wherein—

Figure 1 is a longitudinal vertical sectional view taken through one end of a device constructed in accordance with an embodiment of my invention;

Fig. 1^a is a longitudinal vertical sectional view taken through the opposite end portion of the device as herein disclosed;

Fig. 2 is a view in top plan with parts broken away of one end portion of the device as herein embodied;

Fig. 2^a is a view in top plan with parts broken away of the opposite end portion of the device as herein set forth;

Fig. 3 is a sectional view taken substantially on the line 3—3 of Fig. 1;

Fig. 4 is a fragmentary view in elevation illustrating a bumper as herein included;

Fig. 5 is an enlarged fragmentary view in top plan of the discharging end portion of the box;

Fig. 6 is a sectional view taken substantially on the line 6—6 of Fig. 5;

Fig. 7 is an enlarged fragmentary view taken transversely of the box illustrating in detail an embodiment of agitating members;

Fig. 8 is a fragmentary sectional view taken substantially on the line 8—8 of Fig. 7;

Fig. 9 is a fragmentary sectional view

taken substantially on the line 9—9 of Fig. 7; and

Fig. 10 is an enlarged fragmentary sectional view illustrating a lining which may be employed in connection with the box.

As disclosed in the accompanying drawings, 1 denotes a suitable base or foundation of predetermined dimensions and mounted upon the skids or runners 2 arranged in parallelism and disposed longitudinally of the base or foundation. The skids or runners 2 permit the device to be readily transported from one locality to the other although it is to be understood that 10 when in operation the base or foundation 1 is adapted to be raised to a predetermined elevation and on a slight longitudinal incline.

Resting upon the base or foundation 1 and disposed longitudinally thereof are the parallel angle beams 3 arranged in predetermined transverse spaced relation. Suitably secured to the beams 3 are the upstanding trusses 4 of any ordinary or preferred construction and which are arranged in pairs in longitudinally spaced relation, the trusses of each pair being transversely alined. Each pair of trusses have their upper portions tied or connected by the transverse irons 5 upon which rest the parallel beams 6 extending longitudinally of the foundation and positioned intermediate the trusses 4, as is particularly illustrated in Figs. 2 and 2^a.

35 The upper portion of the trusses 4 intermediate the irons 5 are provided with the transversely alined bearings 7 in which are rotatably supported the angular extremities 8 of the substantially U-shaped hangers 9. 40 The base or intermediate portions 10 of the hangers 9 are pivotally engaged, as at 11, with the transverse strips 12 secured to the upper edges of the sides 14 of the box B. By this arrangement it will be perceived 45 that the box B may be readily and conveniently vibrated.

The discharge end of the box B is open while the opposite end 15 is arranged on a predetermined downward and forward incline and the sides 14 of the box B immediately adjacent the closed or receiving end 15 are provided with the upstanding extensions or wings 16. The end portion of the box B provided with the wings or extensions 16 55 underlies the discharge end of the hopper H into which the value bearing material to be separated is initially deposited in any manner which best suits the requirements of practice.

60 The closed end 15 at its upper portion is provided with the outwardly directed and transversely spaced webs 17 connected by the rod 18. Pivots engaged with the rod 18 is the rigid link or plate 19 which plate

or link is also pivotally engaged, as at 20, 65 with the crank 21 of the shaft 22 supported by the transversely alined bearings 23 suitably mounted upon the base or foundation 1.

One end portion of the shaft 22 is operatively engaged, as at 24, with the driving 70 shaft 25 extending longitudinally of the base or foundation 1 and positioned adjacent the outer side of one of the angle beams 3. The shaft 25 is suitably mounted within the bearings 26 carried by the base or 75 foundation 1, and said shaft 25 at a predetermined point intermediate its length has affixed thereto the pulley 27 adapted to be connected with any suitable source of power. While I show a pulley 27 affixed to the shaft 80 and with which a belt is adapted to coact, it is to be understood that any desired means may be employed for imparting the requisite rotation to the shaft 25.

The box B is of such a length as to have 85 its discharge end extend beyond the adjacent end portion of the base or foundation 1 and said extended portion is provided in its bottom 28 with the transversely spaced openings 29 in communication with the receptacles or wells 30 depending from the extended portion of the box B. The bottom of each of the wells or receptacles 30 is open 90 and has coacting therewith a slide valve 31.

During the operation of my improved device the heavier material or concentrates will be received or collected within the wells or receptacles 30 and when desired the same may be readily and conveniently emptied by the removal or opening of the valves 31. 95 The material collected within the wells or receptacles 30 is preferably delivered to portable receptacles positioned therebeneath as it has been found in practice that the heavier material or concentrates retained 100 within the receptacles or wells 30 is substantially virgin metal.

The beams 6 are also provided with the transversely alined bearings 32 with which are rotatably engaged the angular extremities 33 of the substantially U-shaped hangers 34. The bases or intermediate portions 35 of said hangers are pivotally engaged, as at 36, with the elongated plate 37 positioned intermediate the sides 14 of the box B and substantially entirely closing the same. The plate 37 is also positioned adjacent the upper edges of the sides 14 and is of such a length as to extend from substantially the inner ends of the wings or extensions 16 to 115 the forward edges of the openings 29 so that said plate will overlie the receptacles or wells 30 hereinbefore referred to.

The portion of the plate 37 adjacent the discharging end of the box B has pivotally 125 engaged with the upper surface thereof, as at 38, the inwardly directed rigid link or plate 39 which is also operatively engaged

with the crank 40 of the transverse shaft 41, each end portion of which being rotatably supported by a bearing 42 extending upwardly from the base or foundation 1.

5 An end portion of the shaft 41 is operatively engaged, as at 43, with the shaft 25 hereinbefore referred to whereby it will be at once understood that the shafts 22 and 41 will be caused to rotate in unison. It is also 10 to be noted that the cranks 21 and 40 are reversely directed so that while the box B and plate 37 will be reciprocated or vibrated in unison, the movements thereof will be in reverse directions.

15 The sides 14 of the box B adjacent the discharge end thereof have engaged therewith through the medium of the transverse member 44, the upstanding sides 45 of an apron 46, said apron and its sides extending 20 within and overlying the lower or receiving end portion of the upwardly inclined trough 47, said trough being preferably substantially U-shape in cross section. The trough 47 is maintained in applied position through 25 the medium of the brace irons or struts 48. I wish to state at this time that I do not desire to limit myself to any particular manner for maintaining the trough 47 in applied position.

30 The discharging end portion of the bottom 28 of the box B has positioned at opposite sides of each of the openings 29 the forwardly converging walls 49 terminating in substantially parallel portions 50 intersecting the inner portion of the apron 46, and the upper marginal portions of said substantially parallel parts 50 are operatively engaged with the member 44 hereinbefore referred to. The portions 51 of the

35 apron 46 intermediate the parallel parts 50 are capable of vertical adjustment so that the same may be raised or lowered relative to the underlying portion of the discharging end of the bottom 28 of the box B or 40 that portion of the bottom 28 of the box B in advance of the openings 29. The portions 51 serve as skimming elements whereby it will be at once self-evident that the lighter material will be caused to pass over

45 the elements or portions 51 so that the waste or by-products comprised in the lighter material may be carried upwardly of the trough 47, while the heavier material or concentrates not collected within the 50 wells or receptacles 30 may be discharged upon the oppositely directed and downwardly inclined chutes 52. The chutes 52 as herein embodied are supported in applied position through the medium of the angle irons 53 suitably secured to the base or foundation 1.

Underlying the plate 37 and co-extensive therewith is a supplemental plate 54. The plates 37 and 54 are secured one to the

other in any desired manner, as indicated 65 at 55.

The plate 54 is provided with a plurality of depending agitating members 56 which may be as desired, and it is preferred that certain of said members 56 be elongated, 70 as indicated at 57, so as to extend within the wells or receptacles 30 so that the heavy material or concentrates collected thereby may also be agitated for a purpose which is believed to be clearly apparent to those 75 skilled in the art to which my invention appertains.

It has also been found of advantage to provide the end of the plate 37 with the upstanding guard or shield 58 extending 80 above the discharge opening 59 in the hopper H, whereby it will be perceived that the material as delivered from the hopper H will be caused to fall within the receiving end portion of the box B.

It is also to be understood that suitable means is to be employed for causing the by-products or waste material delivered to the trough 47 to travel upwardly thereof and as herein disclosed, this result is accomplished through the medium of the endless members 60 operatively engaged with the transverse shafts 61 positioned adjacent the opposite end portions of the trough 47. The endless members 60 are connected by 95 the transverse blades 62 which are adapted to engage the material as delivered to the trough and carry the same upwardly thereof. One of the shafts 61, preferably the outer or uppermost shaft, is operatively connected, as at 63, with the shaft 41 hereinbefore referred to whereby it will be at once self-evident that the endless members 60 100 will be driven from the shaft 25.

As has been hereinbefore set forth, the 105 base or foundation 1 when mounted for operation is disposed on a predetermined downward incline toward the discharging end of the box B. It will therefore be at once self-evident that the converging walls 49 will retard the flow or travel of the value bearing material and increase the depth thereof at the discharging end portion of the box B which provision, in practice, has proven of utmost importance.

The vertical adjustment of the free end portions of the skimming elements 51 permits the same to be set in accordance with the necessities of practice and while this vertical adjustment may be effected in any 110 desired manner, I prefer to employ the arrangement disclosed in the accompanying drawings and wherein a transverse beam 64 is carried by the discharging end of the box B and disposed above the straight portions 50 of the walls 49. Depending from said beam 64 are the threaded shanks or members 65 operatively engaged with the 115 120 125

free end portions of the skimming elements 51 through the medium of the nuts 66 arranged above and below said elements.

While the agitating members coacting with the plate 37 may be as desired, I find it of especial advantage and importance to employ the members M as particularly illustrated in Figs. 7, 8 and 9. In this embodiment, the members M are arranged in staggered relation as particularly disclosed in Fig. 9 and each of said members M is substantially U-shape in form with its side arms 67 disposed on a predetermined rearward incline as disclosed in Fig. 8 so that the intermediate or base portion 68 of said member will be inclined downwardly and forwardly. By this arrangement it will be perceived that upon the forward movement of the plate 37^a the intermediate or base portion 68 will serve in the nature of a scoop so that in addition to agitating the value bearing material it will cause said material to advance or move forwardly. To further effect the requisite travel of the value bearing material I also find it of extreme importance to have the side arms 67 of the member disposed transversely in forward convergence, as is believed to be clearly illustrated in Figs. 7 and 9. With the side members 67 and the base or intermediate 68 arranged as just described, it will also be self-evident that upon the rearward movement of the plate 37^a, the member M will pass freely therethrough without materially effecting the flow of the value bearing material. The upper or free extremities of the side arms 67 are angularly disposed, as at 69, and said angular portions 69 contact with the under face of the plate 37^a and are suitably secured thereto, as indicated at 70.

If preferred, the box B or more particularly the bottom 28 thereof may be provided with a lining L as indicated in detail in Fig. 10. The lining L as herein disclosed comprises a bottom or lower lamination 71 of a relatively fine metallic mesh, and resting upon the lamination 71 is a second lamination 72 of a coarse porous textile fabric. Resting upon the lamination 72 is a third lamination 73 consisting of a metallic fabric of a relatively large mesh and of a heavier material than the lamination 71. The lining L serves as an effective medium to retain flour gold or the like and the upper metallic lamination 73 serves as an effective guard or protection in the event the agitating members 56 or M should come in contact with said lining L.

It has also proven of advantage in practice to provide means coacting with the box B to bring the same to an abrupt stop on its forward movement. As herein embodied, I provide the rear edge or face of a pair of trusses 4 with the rubber-faced blocks 74

with which are adapted to contact the bumpers 75 extending laterally from the sides 14 of the box B. As is particularly illustrated in Fig. 4, it is to be noted that each of the bumpers 75 is capable of adjustment longitudinally of the box B in order that the same may be set in the manner which best meets the requirements of practice. It is thought to be self-evident that as the bumpers 75 engage the blocks 74 the box B will be brought to an abrupt stop which further facilitates the agitation of the value bearing material therein and which also further facilitates the travel of such material toward the discharge end of the box.

From the foregoing description, it is thought to be obvious that a sluice constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. A device of the character described comprising a box, and a vibratory member coacting with said box and provided with agitating means extending within the box, 100 said agitating means consisting of a substantially U-shaped member having its side portions arranged transversely in divergence toward the discharge end of the box.

2. A device of the character described comprising a box, a vibratory member coacting with said box and provided with agitating means consisting of a substantially U-shaped member having its side portions arranged transversely in divergence 110 toward the discharge end of the box, the base portion of said U-shaped member being transversely inclined downwardly toward the discharge end of the box.

3. A device of the character described including a box mounted for vibratory movement and having one end open, a rod disposed transversely of the box adjacent the open end thereof and at a predetermined distance above the bottom of the box, a 120 trough positioned in advance of the open end of the box, an apron provided with upstanding side walls, said walls being secured to the transverse member, said apron extending within the trough, a collecting receptacle depending from the box inwardly of but in close proximity to the apron, said collecting receptacle being in

communication with the box through the bottom thereof, and forwardly converging walls carried by the box and positioned at opposite sides of the communication between the box and receptacle, the forward end portions of said walls terminating in substantially parallel portions intersecting the portion of the apron extended within the box, said substantially parallel portions

of the last named walls being operatively 10 engaged with the transverse member.

In testimony whereof I hereunto affix my signature in the presence of two witnesses.

CHARLES E. BROWN.
